UNITED STATES PATENT OFFICE.

CLARENCE LEON GEORGE AND HENRY HART, OF LONDON, ENGLAND, ASSIGNEES TO LINOTYPE AND MACHINERY LIMITED, OF LONDON, ENGLAND, A LIMITED LIABILITY COMPANY OF GREAT BRITAIN.

TYPOGRAPHICAL COMPOSING-MACHINE.

1,351,288.

Specification of Letters Patent. Patented Aug. 31, 1920.

Application filed April 30, 1919. Serial No. 293,818.

To all whom it may concern:

Be it known that we, CLARENCE LEON GEORGE and HENRY HART, a citizen of the United States of America, and a subject of the King of the United Kingdom of Great Britain and Ireland, respectively, and residing at 188 and 189 Fleet street, London, England, have invented new and useful Improvements in Typographical Composing-Machines, of which the following is a specification.

This invention relates to typographical composing machines particularly those known commercially under the trade-mark "linotype" and more especially those of the class which is equipped with columns of superposed magazines adjustable to bring any of them into and out of working position.

Among the principal objects of the invention, there may be mentioned the construction of machines of the just-named class so that the number of the magazines comprised in the columns thereof can be increased or decreased without involving any constructional alterations, and so that any of the said magazines can be removed and replaced without disturbing any other magazines of the column more readily than has heretofore been possible.

The invention may be said to involve a system of construction wherein each magazine together with its frame and the support for such frame, constitutes a unit and as such, can be added to, or removed from, the other units of which the adjustable column is composed, and wherein also a lower magazine together with its frame can be slid forward and backward without necessitating the raising or disturbance of an upper magazine.

The invention will now be more particularly described by reference to the accompanying drawings in which:—

Figure 1 is a side elevation of as much of a linotype machine as is necessary to illustrate the present invention.

Fig. 2 is a plan of Fig. 1 with parts broken away and shown as viewed in a direction perpendicular to the top surface of the top magazine at its normal angle.

Fig. 3 is an elevation as viewed from the bottom of Fig. 2 of a part of the devices shown in that figure.

Fig. 4 is a side elevation corresponding to a part of Fig. 1 and showing the middle magazine in course of removal, the top magazine being omitted from the said figure.

Fig. 5 is a plan corresponding to a portion of Fig. 2.

Fig. 6 is a view similar to Fig. 5 showing certain locking devices in relatively different positions.

Fig. 7 is a front elevation of Fig. 6 and

Fig. 8 is an elevation as viewed from the left-hand side of the machine, of a lower part of the column of magazines illustrative of certain details of the locking mechanism.

Like reference numerals are used to indicate like or corresponding parts, throughout the several figures of the drawings.

As a means of illustrating one convenient manner of carrying out the present invention, the machine represented in the accompanying drawings is shown as equipped with a column of three magazines 11, 12 and 13, these being hereinafter referred to respectively as the top, middle and lowest magazine; when the column comprises more than three magazines, as may conveniently be the case, the supplemental or additional magazine or magazines is or are located between the magazines 12 and 13.

As little or no difficulty is ever experienced in removing the top magazine of a column by the means heretofore available, the present invention does not concern itself with those means, and for that reason the devices for attaining that result, which have been arbitrarily selected for illustration in Figs. 1 and 2, and which are themselves of ordinary well-known construction, are not to be regarded as, *per se*, forming any part of the present invention. The said illustrated means comprise two lifting cams 14 each pivoted to one side of the topmost magazine frame 15 by a stud or shaft 16 and bearing on a roller 17 (one of which is shown in dotted lines in Fig. 1) pivoted on the inside of the uppermost side walls 18 of the column. Each lifting cam 14 is formed on, or rigidly secured to, a hooked arm 19 which, when rocked forward into

the position indicated in dot-and-dash lines in Fig. 1, serves for supporting the magazine 11 during its removal, the two ends of

a bar 20 (Fig. 2) secured to the underside of the magazine, at that juncture, resting on the then-forwardly projecting ends of the two hooked arms 19. The upper or rear 5 part of the magazine frame 15 is supported on a horizontal rod or tie-bolt 21, extending transversely through or beneath it, said tie-bolt, in turn, being supported by the before-mentioned uppermost side walls 18, which 10 it, conjointly with a second tie-bolt 22, serves to brace together as a rigid entity.

To the forward or lower end of the two walls 18, is secured the bank of escapements 23 (shown in dotted lines in Fig. 1) 15 pertaining to the top magazine 11, the arrangement being such that when the hooked arms 19 are in their rearmost position, in which they are shown in full lines in Fig. 1 and in dot-and-dash lines in Fig. 2, the 20 magazine 11 will be in operative engagement with the escapements 23, and when the hooked arms 19 are in their foremost position in which they are shown in dot-and-dash lines in Fig. 1, the magazine 11 will, 25 as correspondingly shown in dot-and-dash lines in that figure, be raised out of mesh with the escapements 23 so as to admit of the said magazine being lifted out of engagement with its frame 15 and drawn forward over the escapements without contacting therewith, preparatory to the support of the magazine 11 being transferred to the hooked arms 19 and the subsequent lifting off of that magazine from the said arms, 30 by the operator.

The replacement of a top magazine 11 on the column, is effected by carrying through in the reverse order, the just described operations involved in removing such a magazine.

The before mentioned uppermost side walls 18 are those which appertain to the middle magazine 12, these two walls being rigidly bolted as shown by bolts 24, or 45 otherwise secured to other walls 25 beneath them, appropriated to the lowest or next lower magazine 13. The two walls 25 appertaining to the lowest magazine, may be cast integral with, or rigidly secured to, a spider or frame 26 extending from one to the other of such walls, this spider or the walls 25 being provided with means such as coaxial rollers 27, which assist in guiding the column when it is moved to bring different magazines into operative position.

To insure the correct relative positioning of the different superimposed walls 18, 25 and frame 26, perfect registration may be secured by means of dowel connections 28 which may, as shown in Fig. 1, take the form of sockets and spigots concentric with the bolts 24.

Various means are already known for moving columns of magazines as before mentioned and any of those which may be found

suitable, can be used in connection with the present invention. Thus, in the example illustrated in part in Fig. 1, the known means employed consist of toggle links 29 pivoted to the underside of the frame 26, 70 to whose lower ends are pivoted other toggle links 30 which are rigidly secured to two rocking shafts 31 on which are also secured two lever arms 32 connected together by a link 33, so that the two shafts 31 will always 75 be rocked in unison, this movement being effected by the operator through the medium of a hand lever fast on the foremost of the two rocking shafts 31. For convenience of illustration the last-mentioned shaft and 80 the members directly connected thereto have been omitted from Fig. 1, but the devices are of such well-known construction that they do not call for special representation.

During the before-mentioned adjustment 85 of the column of magazines this column is constrained to move in a straight path by the aforesaid rollers 27, which are pivoted to the frame 26, and travel along track rails 34 rigidly attached to the so-called 90 distributor bracket 35 or to the main frame or other convenient part of the machine; in this same figure only the right-hand of the two coaxial rollers 27 is shown, this being represented in dotted lines in its 95 uppermost position, and in dot-and-dash lines in its lowermost position, the lowermost position of the magazine column being correspondingly indicated by the dot-and-dash lines marked 26.

On the inner face of each of the side walls 18, 25 there is provided a track or rail 36 on which is supported, with a capacity for limited forward and backward movement, a frame 37 which, itself, supports the 105 respective magazine 12 or 13 and its escapements; for more readily distinguishing the frames 37 from the other frames hereinbefore mentioned, said frames 37 are herein-after referred to as sliding frames.

Of the magazines heretofore used, there are two distinct types, one in which the escapements are permanently attached to and removable with the said magazines, and the other in which the escapements are separable from the magazines and remain on the machine when a magazine is removed therefrom, ready for engagement with a substitute magazine.

The arrangement represented in the accompanying drawings embodies escapements which are separable from the magazines, but this is to be regarded merely as an example because certain parts of the invention are also applicable to machines in which the escapements are removable with the magazines. When, however, the arrangement is constructed as shown in the drawings, each of the sliding frames 37, in accordance with the present invention, has pivoted to its front 130

end, as by a transverse shaft 38, two blocks 39, 40 which virtually form extensions of the sides of that sliding frame and, like the latter, are movable forward and backward 5 along the rails 36. As the two sliding frames 37 and their respective magazines 12 and 13, and the appurtenances directly connected or coöperating therewith are practically identical the following description, which is generally restricted to the middle magazine 12 and the frame 37 thereof, is equally applicable to the lowest magazine 13 and its sliding frame 37.

The bank of escapements 41 of the said magazine 12 is supported by the two blocks 39, 40 so that when the latter are in their normal rearmost position wherein they are alined with the sides of the sliding frame 37, the escapements 41 are in perfect register 20 and mesh with the magazine, and when the said sliding frame is in its foremost position, the blocks 39, 40 are lowered so that the escapements are clear of the magazine, as shown as an example in connection with the 25 middle magazine 12, in Fig. 4, so that that particular magazine can then be removed frontwise of the machine without contacting with, or damaging, the said escapements. The illustrated example represents this result as attained by forming an angular recess bounded by the relatively inclined surfaces 42, 43 in the underside of each block 39, 40 at a short distance rearward of the front end of that block, the said front end 30 however having its under surface in such a plane as will insure, during the normal working of the machine, the said block being supported in the position necessary for maintaining the above mentioned enmeshment of 35 the escapements and magazine, and, indeed, through said blocks, lifting the magazine slightly off its sliding frame 37 as herein-after more particularly described.

When, with the just described arrangement, the sliding frame 37, is allowed to move to its foremost position on the track rails 36, the blocks 39, 40 pivoted to, and traveling with, that frame, maintain their alinement with the latter until the inclined surfaces 42 reach the front ends of the track rails 36, after which juncture the continued forward movement of the sliding frame causes the blocks 39, 40 to pivot downwardly on the shaft 38, this continuing until, at the 55 end of such forward movement, the inclined surfaces 43 of the blocks contact with the surfaces of the rails 36; this contact serves to arrest further descent of the said blocks which thereafter, support the escapement in 60 such a position as will admit of the magazine being moved over it without contacting therewith.

In view of the desirability, in the carrying out of the present invention, to utilize, as far 65 as possible, elements and fittings which are

of standard construction, and in view of the fact that the before described mutual engagement and disengagement of the escapements 41 and magazine 12 or 13, is effected on curvilinear lines of comparatively short 70 radius, as distinguished from, as heretofore, curves of long radius or indeed rectilinearly, we prefer to mount the said bank of escapements in the blocks 39, 40 so that it can rock therein to a slight extent and thereby enable the intermeshing parts of that bank, as it were, to work their way into and out of engagement with the complementary parts on the magazine. This result, as shown in the drawings, may be conveniently attained 80 by providing a trunnion 44 on each end of the bank of escapements 41, and a bearing 45 for supporting said trunnion, on the inner side of the respectively adjacent block 39 or 40. The bearings 45 are preferably 85 open at the top so as to enable the bank of escapements to be readily lifted out of the machine for cleaning or other purposes, accidental displacement of said bank being prevented by maintaining the trunnions 44 90 in the bearings 45, by easily removable means such as caps or the screws 46 which latter penetrate the said bearings 45, closely overlie the trunnions 44, and must be withdrawn before the escapement bank can be 95 removed.

The aforesaid rocking motion of the escapement bank 41 is caused by springs 47 each encircling one of the trunnions 44, as shown in Figs. 2, 5, 6 and 7. Of the two 100 springs, 47, the left-hand one, at its respectively opposite ends, engages with a horizontal pin 48 fast to the adjacent bearing 45 and a flange 49 integral with the respective trunnion 44, said flange serving for the attachment of that trunnion to the adjacent end of the escapement bank 41, while the respectively opposite ends of the right-hand spring 47 engage with a stop collar 50 adjustably secured on the right-hand trunnion 110 44, and a stop or abutment 52 projecting inward from the adjacent bearing 45, the stop collar being provided with an arm or projection 51, Figs. 2 and 4, adapted to engage with the said stop or abutment 52. 115

When the machine is in normal working condition and the escapement bank 41 is properly enmeshed with its magazine, the arm 51 is just out of contact with the abutment 52, as shown in dotted lines in Fig. 4, 120 in connection with the lowest magazine 13, but when the said escapement bank is lowered out of mesh with its magazine, as shown in Fig. 4 in connection with the middle magazine 12, the springs 47 have rocked that bank clockwise, as viewed in that figure, until stopped by the arm 51 contacting with the abutment 52. When, during the reinstatement of a magazine into the machine, the escapement bank is automatically raised into 125 130

engagement with the said magazine, the springs 47 allow of an easy mutual engagement of the said bank and magazine, the former, as it were, automatically adapting 5 its position to suit the gradually varying conditions necessitated by such engagement.

To insure that the engagement of the banks of escapements with the complementary parts of the respective magazines shall 10 be as close and efficient as possible, the blocks 39, 40 are so formed that when in their normal rearmost position, they support the escapement banks 41 at such a height that the front ends of the said magazines are slightly raised off the sliding frames 37 and the entire weight of these ends is born by the said escapement banks.

The two ends of each of the before described transverse shafts 38 project outward 20 beyond the side walls 18, 25 which, as shown best in Figs. 1 and 4, are provided with slots 53 wherein that shaft is capable of sliding fore-and-aft of the machine, the length of these slots 53, if desired, serving 25 to limit the extent of the said motion and consequently the corresponding motion of the respective sliding frame 37.

On the outer ends of each shaft 38, loose ferrules 54 may be provided to serve as handles by which the fore-and-aft movement of 30 the respective sliding frame 37 can be controlled or effected by the operator.

Pivoted to a bracket 55, fast on each of the side walls 18, 25, there is provided a bell-crank lever 56, of which one arm is so located that it can be easily engaged by a finger of the operator when he grasps the before mentioned handle 54, while the other arm is pivotally attached to a locking bolt 40 57 which, under the action of a spring 58 normally engages with a recess in the adjacent side of the sliding frame 37, to retain the said frame in operative position. When it is desired to release the sliding frame 37 45 so as to allow it to descend into its foremost position, the bolts 57 at either side of the magazine column, can be readily withdrawn out of engagement with the said frame by means of the two bell-crank levers 56, and 50 after such disengagement the thus-released frame 37 can slide down the track rails 36 under the control exercised thereon by the operator through the handles 54, the bolts 57 meanwhile bearing on the outer surfaces 55 of the descending frame, until such time as other recesses 59 are brought into register with the bolts 57 which thereupon, under the influence of their springs 58 engage with those recesses and thereby serve to retain 60 the sliding frame in position during the period that another magazine is being slid backward thereon for insertion into operative position in the machine. The two pairs of recesses with which the locking bolts 57 65 engage are of such size as to enable the

sliding frame 37 to be moved by the operator slightly rearward to relieve the said bolts of the pressure which would otherwise hamper their withdrawal.

In many machines as heretofore constructed, the magazines are prevented from sliding forwardly on their frames by transverse bars on the underside of the former engaging with upwardly-projecting hooks or ribs on the latter, the front ends of the 70 magazines having to be raised sufficiently to disengage the bars from the hooks before the magazines can be removed from the front of the machine. Where the space between the adjacent superposed magazines of 75 the present improved machine is sufficient to admit of the just-named raising of the magazines, corresponding means can be employed for the purpose, but where the said space is not sufficient for that purpose, then 80 the disengagement of the magazine 12 from its sliding frame 37 may be effected by means such as those next described, which, in no way involve the lifting of the magazine.

The means just referred to, as illustrated 90 in Figs. 2, 4, 5 and 6, comprise two sliding bolts 60 guided in the respective sliding frame 37 so as to be capable of moving only vertically or approximately vertically there-in. When the bolts 60 are in their uppermost position, their upper ends are directly at the front of, and in contact with, the above named transverse bar 61 and thereby serve to prevent any forward movement of 95 the magazine 12. The two bolts 60 are pivotally connected to the forward ends of levers 62 whose rear ends are pivoted as by short shafts 63 to the sliding frame 37, and the lowering and raising of the bolts 60 is effected by means of eccentrics 64, Figs. 4 100 and 5, each operative between two cheeks or projections 65 on the respective lever 62, and rigidly secured on the before described shaft 38 on which is also rigidly secured a hand lever 66. By reference particularly to Figs. 110 2, 5 and 6, it will be seen that the connection between the bolts 60 and the sliding frame 37 is effected by a dovetail rib on the former which is slidable within a dovetail groove in the latter. In order to prevent 115 accidental turning of the shaft 38 from either of its two terminal positions, the sliding frame is provided with two spring-pressed detents 67 which are each capable of engaging with two V-shaped notches 120 formed in the just mentioned dovetail rib in positions corresponding with the two terminal positions of the sliding bolts 60.

In the arrangement as illustrated in full lines in Fig. 2, it would be possible to operate the hand lever 66 before the sliding frame 37 had been moved into its foremost position and consequently cause damage by the premature sliding off of the magazine, and to secure against any such contingency 130

we prefer to provide means which shall render the hand lever 66 inaccessible for operation until such time as it is safe to be operated. One way of attaining that result would be, as shown in dot-and-dash lines in Fig. 2, to provide a guard-plate or projection 68 fast on, and extending inwardly from, the side wall 18 in such position that when the hand lever 66 is in its normal rearmost position, that lever is closely overhung by the said guard-plate.

It is necessary to insure that the bank of escapements 41 shall not be detached from the magazine 12 until after the matrices 69, Fig. 1, shall have been locked therein. Means controlled by the matrix-locking strip or poker 70, are already known which will fulfil a corresponding function in connection with the top magazine 11 and those means may be employed in the present arrangement for that particular magazine of the column, but for the lower magazines 12, 13, it is preferred to attain the result in question by the following means.

The left-hand block 39 of the two before described ones 39, 40, is provided with a spring-actuated bolt 71 adapted to engage with a recess or, as shown in dotted lines in Figs. 2 and 5, with the front end of the adjacent slot 53 in the respective side wall 18 or 25. This bolt is axially slideable in a hollow stud 72 screwed into or otherwise fast to the block 39, and on which is pivoted a two-armed bracket 73, 74. To the bracket arm 73 is pivoted a bent lever 75 whose lower end, as shown best in dotted lines in Fig. 8, is forked and embraces the reduced stem of the bolt 71 just to the left-hand side of a collar 76 fast on that stem. The upper end of the bent lever 75 terminates in a head or button 77 which is normally aligned with the channel 78 into which the matrix-locking strip or poker 70 is inserted in the magazine, the position of the said head 77 being such that when the said poker is pushed "home" through the magazine, the left-hand end of the poker, as shown in Figs. 6 and 7, will bear against that head and thereby swing the lever 75 about its pivot and withdraw the bolt 71 clear of the respective side wall 18 or 25. It will be seen therefore that, by this arrangement, the magazine sliding frame 37 is prevented from being moved forward (even though the locking bolt 57 may have been withdrawn) unless and until the matrices are first locked in the magazine by the insertion of the bar or poker 70, so that the accidental spilling of the matrices is entirely obviated.

In order to prevent damage which might otherwise occur were means not provided for lowering the bracket 73, 74 and lever 75 out of the path through which a magazine 12 or 13 is moved out of the machine, the following devices are employed by which

that result is attained automatically during the forward movement of the respective sliding frame 37. It has already been explained that the bracket 73, 74 is pivotally mounted on the hollow stud 72, and it remains now to be explained how the rocking of the said bracket on that stud is effected. For this purpose the second arm 74 of the bracket 73, 74 is provided with a pin 79 rigidly attached to and extending transversely through it, and having attached to it, on the right-hand side of the said arm, one end of a helical spring 80 whose other end is attached to an eye 81 fast to the respective sliding frame 37, as shown best in dotted lines in Fig. 4. The left-hand end of the pin 79 is arranged to bear against an abutment 82 rigidly secured to the respective adjacent wall 18 or 25 or, more particularly, as shown, to the track rail 36 of that wall, this being the condition which obtains when the sliding frame 37 is in its normal rearmost position, and as a result thereof the bent lever 75, is held in its highest position against the action of the spring 80, with its head 77, as shown best in Fig. 8, in the path of the poker which, may afterward be pushed through the respective channel 78. When the sliding frame 37 moves forward, the pin 79 moves away from the abutment 82 and the spring 80 swings the bracket 73, 74 about the hollow stud 72 and thereby lowers the lever 75 out of the path through which the magazine 12 or 13 will afterward be moved during its removal from the machine, as shown best in Fig. 4 in connection with the magazine 12.

For facilitating the removal and replacement of the magazines 12, 13, arms or brackets 83, such as the one shown in dot-and-dash lines in Fig. 4, can be provided for receiving those magazines while the latter are being slid off and on to their respective sliding frames 37. These brackets, as shown, can be temporarily attached to the side walls 18 or 25, by hooking under studs 84 rigid upon the said side walls, and over the then-advanced handles 54, or in any other convenient manner, and they are so shaped that when they are in operative position, their magazine-supporting ledges virtually form continuations of the respective sliding frames 37.

If desired, the before-described locking bolt 71 may be arranged to control the release of the adjacent bolt 57 in such a way that the latter cannot be withdrawn until after the poker 70 has been inserted in the respective magazine 12 or 13 to lock the matrices 69 in the latter. This result might, for example, be obtained by means such as that shown in dotted lines in Fig. 2, comprising an angular trigger lever 85 pivoted to the respective side wall 18 or 25 in such near location to the bolt 57 that one of its

arms is movable into and out of the path of that bolt, and another similarly pivoted lever 86 engaging at one end, the second arm of the lever 85 and at the other end projecting into the path of the bolt 71, a spring 87 acting on the lever 86 so as to tend always to move or retain the lever 85 out of the path of the bolt 57. By this arrangement the bolt 57 engaged by the lever 85, when in engagement with the respective sliding frame 37 that is to say, when the said frame is in its normal working position, cannot be disengaged from that frame until the poker 70 has been pushed "home" in the respective magazine 12 or 13 for locking the matrices therein, this operation serving both to withdraw the bolt 71 and simultaneously therewith render the adjacent bolt 57 capable of being manually withdrawn immediately thereafter.

The right-hand side walls 18 and 25 are formed with recesses 88 for giving access to the poker channels 78 when the magazines 12, 13 are in their normal rearmost position.

For absorbing any shock which might be caused by the too violent lowering of a sliding frame 37, buffer springs 89 threaded on rods 90 may be interposed between cross heads or eye bolts 91, 92 secured respectively to the said sliding frame and to the respectively adjacent track rail 36.

In a machine wherein it may not frequently be required to change the lower magazines, the escapement banks of these magazines may be pivoted, as hereinbefore described, to the sliding frames 37 but otherwise be so arranged that their engagement and disengagement with the said magazines shall be effected by hand; or, indeed, the said magazines could have their banks of escapements permanently attached to them, in which arrangement the operation of removing a magazine need involve little more than the sliding forward of the respective frame 37 and the disengagement of the said magazine from that frame either by the lowering of the respective bolts 60 or the raising of the magazine out of engagement with the equivalent of the said bolts.

In the last mentioned arrangement the blocks 39, 40 would not be necessary and in the place thereof there might be provided hooked arms which, when the sliding frames 37 were in their foremost position, would project to the front of the magazine column and serve, in like manner to the before described arms 19 and 83, to temporarily support the magazines during their removal and replacement.

The distributor mechanism 93 and the assembled entrance 94 shown in Fig. 1, call for no special description, as they constitute no separate part of our invention, and it will therefore now suffice to explain that the before described magazine-column lift-

ing devices are, as ordinarily, so devised as to enable any one of the magazines 11, 12, 13 to be brought into operative register simultaneously with the said organs 93, 94. In machines in which the so-called assembler plate cannot be swung away from the front of the magazines, the magazine-column lifting devices are so designed as to enable the lowest magazine to be raised sufficiently high to admit of it clearing the top of such assembler plate during the subsequent act of removal or replacement; in machines in which (as in many of those already in use) the assembler plate can be swung away from the magazines, this extent of lift obviously will not be necessary.

It is to be understood that the before-described embodiment of the present invention is given merely as a convenient example, and that the same may be modified in various ways without departing from the spirit of such invention, for instance, many of the features of the invention may be embodied in those known machines in which the columns of magazines are stationary and the assembler entrances are adjustable into register with and relatively to the different magazines.

Having thus described our invention, its construction and mode of operation, what we claim and desire to secure by Letters Patent of the United States is as follows:—

1. In a typographical composing machine having a plurality of superposed magazines, the combination with a lower magazine of a sliding frame whereon it is removably mounted and a support on which the said frame can slide forward and backward relatively to and without necessitating the raising or disturbance of an upper magazine to locate said lower magazine in convenient position for removal and replacement.

2. In a typographical composing machine having a plurality of superposed magazines, the combination with a lower magazine, a sliding frame whereon it is removably mounted and a support on which the said frame can slide forward and backward relatively to the other magazines, of devices adapted to limit the movement of the said sliding frame and lock that frame in its terminal positions.

3. In a typographical composing machine having a plurality of superposed magazines, the combination with a lower magazine, a sliding frame whereon it is removably mounted and a support on which the said frame can slide forward and backward relatively to the other magazines, of devices adapted to limit the movement of the said sliding frame and lock that frame in its normal position.

4. In a typographical composing machine having a plurality of superposed magazines,

the combination with a lower magazine, a sliding frame whereon it is removably mounted and a support on which the said frame can slide forward and backward relatively to the other magazines, of devices adapted to limit the movement of the said sliding frame and lock that frame in its forward position.

5. In a typographical composing machine having a plurality of superposed magazines, the combination with a lower magazine, a sliding frame underlying it and a support on which the said frame can slide forward and backward, of devices adapted to lock the magazine to the sliding frame and unlock it therefrom without raising the magazine relatively to the said frame.

6. In a typographical composing machine, the combination of a magazine, a sliding frame underlying it, a support on which the said frame can slide forward and backward, devices adapted to limit the movement of the said sliding frame and lock it in its normal position, and devices adapted to lock the magazine to the sliding frame and unlock it therefrom without raising the magazine relatively to the said frame.

7. In a typographical composing machine having a plurality of superposed magazines, the combination with a lower magazine, a sliding frame underlying it and a support on which the said frame can slide forward and backward, of devices adapted to lock the magazine to the sliding frame and unlock it therefrom, and means adapted to prevent such unlocking when the sliding frame is in its normal position.

8. In a typographical composing machine, the combination of a magazine, a sliding frame underlying it, a support on which the said frame can slide forward and backward, devices adapted to limit the movement of the said sliding frame and lock it in its normal position, devices adapted to lock the magazine to the sliding frame and unlock it therefrom, and means adapted to prevent such unlocking when the sliding frame is in its normal position.

9. In a typographical composing machine having a plurality of superposed magazines, the combination with a lower magazine, a sliding frame underlying it and a support on which the said frame can slide forward and backward, of a bank of escapements pivotally attached to the sliding frame, and means adapted to disengage the escapements from the magazine only when the latter is in its forward position.

10. In a typographical composing machine, the combination of a magazine, a sliding frame underlying it, a support on which the said frame can slide forward and backward, and a bank of escapements pivotally attached to the sliding frame.

65 11. In a typographical composing ma-

chine having a plurality of superposed magazines, the combination with a lower magazine, a sliding frame underlying it and a support on which the said frame can slide forward and backward, of blocks pivoted to the sliding frame, bearings on the said blocks, and a bank of escapements pivotally supported in the said bearings.

12. In a typographical composing machine, the combination of a magazine, a sliding frame underlying it, a support on which the said frame can slide forward and backward, blocks pivoted to the sliding frame, bearings on the said blocks, and a bank of escapements pivotally supported in the said bearings.

13. In a typographical composing machine, the combination of a magazine, a sliding frame underlying it, a support on which the said frame can slide forward and backward, blocks pivoted to the sliding frame, bearings on the said blocks, a bank of escapements pivotally supported in the said bearings, a spring adapted to rock the bank of escapements in the bearings, and a device adapted to limit the said rocking movement.

14. In a typographical composing machine having a plurality of superposed magazines, the combination with a lower magazine, a sliding frame underlying it and a support on which the said frame can slide forward and backward, of a bank of escapements pivotally attached to the sliding frame, and means adapted to automatically disengage the bank of escapements from the magazine during the forward movement of the sliding frame.

15. In a typographical composing machine, the combination of a magazine, a sliding frame underlying it, a support on which the said frame can slide forward and backward, a bank of escapements pivotally attached to the sliding frame, and means adapted to automatically disengage the bank of escapements from the magazine during the forward movement of the sliding frame.

16. In a typographical composing machine having a plurality of superposed magazines, the combination with a lower magazine, a sliding frame underlying it and a support on which the said frame can slide forward and backward, of a bank of escapements pivotally attached to the sliding frame, and means adapted to automatically engage the bank of escapements with the magazine during the rearward movement of the sliding frame.

17. In a typographical composing machine, the combination of a magazine, a sliding frame underlying it, a support on which the said frame can slide forward and backward, a bank of escapements pivotally attached to the sliding frame, and means

- adapted to automatically engage the bank of escapements with the magazine during the rearward movement of the sliding frame.
- 5 18. In a typographical composing machine having a plurality of superposed magazines, the combination with a lower magazine, a sliding frame underlying it and a support on which the said frame can slide forward and backward, of a bank of escapements pivotally attached to the sliding frame, and means adapted to automatically disengage the bank of escapements from the magazine during the forward movement of the sliding frame, and engage the said bank with the magazine during the rearward movement of the said frame. 75
- 10 19. In a typographical composing machine, the combination of a magazine, a sliding frame underlying it, a support on which the said frame can slide forward and backward, a bank of escapements pivotally attached to the sliding frame, and means adapted to automatically disengage the bank of escapements from the magazine during the forward movement of the sliding frame, and engage the said bank with the magazine during the rearward movement of the said frame. 80
- 15 20. In a typographical composing machine, the combination of a magazine, a sliding frame underlying it, a support on which the said frame can slide forward and backward, devices adapted to limit the movement of the said sliding frame and lock it in its normal position, devices adapted to lock the magazine to the sliding frame and unlock it therefrom, means adapted to prevent such unlocking when the sliding frame is in its normal position, a bank of escapements pivotally attached to the sliding frame, and means adapted to automatically disengage the bank of escapements from the magazine during the forward movement of the sliding frame and engage the said bank with the magazine during the rearward movement of the said frame. 85
- 20 21. In a typographical composing machine, the combination of a magazine, a sliding frame underlying it, a support on which the said frame can slide forward and backward, devices adapted to limit the movement of the said sliding frame and lock it in its normal position, devices adapted to lock the magazine to the sliding frame and unlock it therefrom, means adapted to prevent such unlocking when the sliding frame is in its normal position, blocks pivoted to the sliding frame, bearings on the said blocks, and a bank of escapements pivotally supported in the said bearings. 90
- 25 22. In a typographical composing machine having a plurality of superposed magazines, the combination with a lower magazine, a sliding frame underlying it, walls between which the sliding frame is movable forwardly and backwardly, and devices adapted to lock the said frame against motion relatively to the walls, of handles on the sliding frame penetrating the said walls and adapted to control the movement of the frame, and means on the walls adjacent the handles whereby the frame locking devices can be manually released. 95
- 30 23. In a typographical composing machine, the combination of a magazine, a sliding frame underlying it, walls between which the sliding frame is movable forwardly and backwardly, devices adapted to lock the said frame against motion relatively to the walls, handles on the sliding frame penetrating the said walls and adapted to control the movement of the frame, and means on the walls adjacent the handles whereby the frame locking devices can be manually released. 100
- 35 24. In a typographical composing machine having a plurality of superposed magazines, the combination with a lower magazine, a sliding frame underlying it, walls between which the sliding frame is movable forwardly and backwardly, a bank of escapements pivotally attached to the sliding frame, and devices adapted to lock the said frame against motion relatively to the walls, of handles on the sliding frame penetrating the said walls and adapted to control the movement of the frame, and means on the walls adjacent the handles whereby the frame locking devices can be manually released. 105
- 40 25. In a typographical composing machine, the combination of a magazine, a sliding frame underlying it, walls between which the sliding frame is movable forwardly and backwardly, a bank of escapements pivotally attached to the sliding frame, devices adapted to lock the said frame against motion relatively to the walls, handles on the sliding frame penetrating the said walls and adapted to control the movement of the frame, and means on the walls adjacent the handles whereby the frame locking devices can be manually released. 110
- 45 26. In a typographical composing machine having a plurality of superposed magazines and matrix-locking means independent of the escapements adapted to lock in the magazines the contents thereof, the combination with a lower magazine, a sliding frame underlying it, a support on which the said frame can slide forward and backward and devices adapted to lock the said sliding frame in its normal position, of devices operable by the matrix-locking means adapted to release the sliding frame. 115
- 50 27. In a typographical composing machine, the combination of a magazine, 120
- 55
- 60
- 65

- matrix-locking means independent of the escapements adapted to lock in the magazine the contents thereof, a sliding frame underlying it, a support on which the said frame can slide forward and backward, devices adapted to lock the said sliding frame in its normal position, and devices operable by the matrix-locking means adapted to release the sliding frame.
- 10 28. In a typographical composing machine, the combination of a magazine, matrix-locking means independent of the escapements adapted to lock in the magazine the contents thereof, a sliding frame underlying it, a support on which the said frame can slide forward and backward, devices adapted to limit the movement of the said sliding frame and lock that frame in its normal position, and devices operable by the matrix-locking means adapted to release the sliding frame.
- 15 29. In a typographical composing machine, the combination of a magazine, a sliding frame underlying it, walls between which the sliding frame is movable forwardly and backwardly, devices adapted to lock the frame against motion relatively to the walls, a bank of escapements pivotally attached to the sliding frame, matrix-locking means independent of the escapements adapted to lock in the magazine the contents thereof, handles on the sliding frame penetrating the said walls and adapted to control the movement of the frame, means 25 on the walls adjacent the handles whereby the frame-locking devices can be manually released, and devices adapted normally to prevent such manual release and operable by the matrix locking means to render possible such manual release.
- 30 30. In a typographical composing machine having a plurality of superposed magazines, the combination with a lower magazine, a sliding frame underlying it, and a support 35 on which the said frame can slide forward and backward, of locking devices normally in the path of a magazine to be removed from the machine and adapted to lock the said sliding frame in its normal position, and devices adapted to automatically move the said locking devices out of the said path during the movement of the sliding frame.
- 35 31. In a typographical composing machine, the combination of a magazine, a sliding frame underlying it, a support on which the said frame can slide forward and backward, locking devices normally in the path of a magazine to be removed from the machine and adapted to lock the said sliding frame in its normal position, and devices adapted to automatically move the said locking devices out of the said path during the movement of the sliding frame.
- 40 32. In a typographical composing machine having a plurality of superposed magazines, 45

- the combination with a lower magazine, a sliding frame underlying it, and a support on which the said frame can slide forward and backward, of escapement-carrying blocks pivotally connected to the sliding frame, locking devices mounted on the said blocks normally in the path of a magazine to be removed from the machine and adapted to lock the said sliding frame in its normal position, and devices adapted to automatically move the said locking devices out of the said path during the movement of the sliding frame.
33. In a typographical composing machine, the combination of a magazine, a sliding frame underlying it, a support on which the said frame can slide forward and backward, escapement-carrying blocks pivotally connected to the sliding frame, locking devices mounted on the said blocks normally in the path of a magazine to be removed from the machine and adapted to lock the said sliding frame in its normal position, and devices adapted to automatically move the said locking devices out of the said path during the movement of the sliding frame.
34. In a typographical composing machine having a plurality of superposed magazines and matrix-locking means independent of the escapements adapted to lock in the magazines the contents thereof, the combination with a lower magazine, a sliding frame underlying it, a support on which the said frame can slide forward and backward, and manually operable locking devices adapted to limit the movement of the said sliding frame and lock that frame in its normal position, of devices adapted to normally prevent the manual operation of the said locking devices and operable by the matrix-locking means to render possible the said manual operation.
35. In a typographical composing machine, the combination of a magazine, and matrix-locking means independent of the escapements adapted to lock in the magazines the contents thereof, a lower magazine, a sliding frame underlying it, a support on which the said frame can slide forward and backward, manually operable locking devices adapted to limit the movement of the said sliding frame and lock that frame in its normal position, and devices adapted to normally prevent the manual operation of the said locking devices and operable by the matrix-locking means to render possible the said manual operation.
36. In a typographical composing machine having a plurality of superposed magazines and matrix-locking means independent of the escapements adapted to lock in the magazines the contents thereof, the combination with a lower magazine, a sliding frame underlying it, a support on which the said frame can slide forward and backward, and

two locking devices, one manually operable and the other normally in the path of a magazine to be removed from the machine, adapted to lock the said sliding frame in its 5 normal position, of devices adapted to automatically move the last-named locking device out of the said path during the movement of the sliding frame, and devices operable by the matrix-locking means adapted to 10 release the first-named locking device.

37. In a typographical composing machine, the combination of a magazine, matrix-locking means independent of the escapements adapted to lock in the magazine 15 the contents thereof, a sliding frame underlying it, a support on which the said frame can slide forward and backward, two locking devices, one manually operable and the other normally in the path of a magazine 20 to be removed from the machine, adapted to lock the said sliding frame in its normal position, devices adapted to automatically move the last-named locking device out of the said path during the movement of 25 the sliding frame, and devices operable by the matrix-locking means adapted to release the first-named locking device.

38. In a typographical composing machine having a plurality of superposed magazines and matrix-locking means independent of the escapements adapted to lock in the magazines the contents thereof, the combination with a lower magazine, a sliding frame underlying it, escapement-carrying 35 blocks pivotally connected to the sliding frame, supports on which the said frame and blocks can slide forward and backward, and two locking devices, one manually operable and the other mounted on one of the 40 escapement-carrying blocks and normally in the path of a magazine to be removed from the machine, adapted to lock the said sliding frame in its normal position, of devices adapted to automatically move the last- 45 named locking device out of the said path during the movement of the sliding frame, and devices operable by the matrix-locking means adapted to release the first-named locking device.

50 39. In or for a typographical composing machine having a column of superposed magazines, a unit insertible or removable as such into or from the said column, comprising two side walls, track rails thereon, a sliding frame movable on the track rails, a magazine supported by the sliding frame, a bank of escapements for the magazine, matrix-locking means independent of the escapements adapted to lock in the magazines 55 the contents thereof, locking devices adapted to limit the movement of the sliding frame and lock that frame in its terminal positions, and means actuated by the matrix-locking means adapted to control the operation 60 of the said locking devices.

40. In or for a typographical composing machine having a column of superposed magazines, a unit insertible or removable as such into or from the said column, comprising two side walls, track rails thereon, a sliding frame movable on the track rails, a magazine supported by the sliding frame, a bank of escapements for the magazine, matrix-locking means independent of the escapements adapted to lock in the magazines 70 the contents thereof, locking devices adapted to limit the movement of the sliding frame and lock that frame in its normal position, and means actuated by the matrix-locking means adapted to control the operation of the said 75 locking devices.

41. In or for a typographical composing machine having a column of superposed magazines, a unit insertible or removable as such into or from the said column, comprising two side walls, track rails thereon, a sliding frame movable on the track rails, a magazine supported by the sliding frame, a bank of escapements for the magazine, matrix-locking means independent of the escapements adapted to lock in the magazines 80 the contents thereof, manually operable locking devices adapted to limit the movement of the sliding frame and lock that frame in its normal position, and devices adapted to normally prevent the manual operation of the said locking devices and operable by the matrix-locking means to render possible the said manual operation.

42. In a typographical composing machine, the combination of a magazine, a sliding frame, walls between which the sliding frame is movable forwardly and backwardly, blocks pivoted to the sliding frame, bearings on the said blocks, a bank of escapements pivotally supported in said bearings, matrix-locking means independent of the escapements adapted to lock in the magazine the contents thereof, manually operable devices adapted to lock the frame against motion relatively to the walls, devices adapted normally to prevent the manual operation of said devices and operable by the matrix locking means to render possible such manual operation, locking devices mounted on one of the escapement-carrying blocks normally in the path of a magazine to be removed from the machine and adapted to lock the sliding frame in its normal position, devices operable by the matrix-locking means to release the last-named locking devices, and means adapted to move said locking devices out of the said path during the movement of the sliding frame.

43. In a typographical composing machine 125 having a plurality of superposed magazines, and matrix-locking means independent of the escapements adapted to lock in the magazines the contents thereof, the combination with a lower magazine of a sliding 130

frame underlying it, a support on which the said frame can slide forward and backward, devices adapted to lock the magazine to the sliding frame and unlock it therefrom without raising the magazine relatively to the sliding frame, means adapted to prevent such unlocking when the said frame is in its normal position, manually operable devices adapted to lock the sliding frame in its terminal positions, devices adapted to normally prevent the manual operation of the said locking devices and operable by the matrix-locking means to render possible the said manual operation, locking devices normally in the path of a magazine to be removed from the machine and adapted to lock the sliding frame in its normal position, devices operable by the matrix-locking means adapted to unlock the sliding frame, and devices adapted to automatically move the said locking devices out of the said path during the movement of the sliding frame.

44. In a typographical composing machine, the combination of a magazine, a sliding frame, walls between which the sliding frame is movable forwardly and backwardly, devices adapted to lock the magazine to the sliding frame and unlock it therefrom without raising the magazine relatively to the said frame, means adapted to prevent such unlocking when the said frame is in its rearward position, blocks pivoted to the sliding frame, bearings on the said blocks, a bank of escapements pivotally supported in said bearings, means adapted to automatically disengage and engage the bank of escapements and magazine during respectively the forward and rearward movement of the sliding frame, matrix-locking means independent of the escapements adapted to lock in the magazine the contents thereof, devices adapted to lock the said frame against motion relatively to the walls, handles on the sliding frame penetrating the walls and adapted to control the movement of the frame, means on the walls adjacent the handles whereby the

frame locking devices can be manually released, devices adapted normally to prevent such manual release and operable by the matrix-locking means to render said release possible, locking devices mounted on one of the escapement-carrying blocks normally in the path of a magazine to be removed from the machine, and adapted to lock the sliding frame in its normal position, devices operable by the matrix-locking means to release the last-named locking devices, and means adapted to move said locking devices out of said path during the movement of the sliding frame.

45. In a typographical composing machine, the combination of a magazine, a bank of escapements therefor, and a pivoted supporting frame arranged to carry the bank of escapements into and out of operative relation to the magazine, the said bank of escapements being rotatably mounted in the supporting frame to insure the proper engagement and disengagement of the escapements and magazine during the movements of said supporting frame.

46. In a typographical composing machine, the combination of a magazine, a sliding frame whereon the magazine is removably mounted, a support upon which the sliding frame is arranged to slide forward and backward in its own plane to facilitate the removal and replacement of the magazine, and means for holding the sliding frame in different longitudinal positions.

47. In a typographical composing machine, the combination of a plurality of superposed magazines, a shift frame therefor movable to bring any selected magazine into operative position, and a sliding frame carrying one of the magazines and arranged to be slid forwardly and backwardly out of and into the shift frame to facilitate the removal and replacement of the magazine thereon.

In witness whereof we have hereunto subscribed our names.

CLARENCE LEON GEORGE.
HENRY HART.
